US00D499119S

(12) **United States Design Patent** (10) Patent No.: **US D499,119 S**
 Thomas, Jr. et al. (45) Date of Patent: **** Nov. 30, 2004**

(54) **COMPRESSOR**

(75) Inventors: **Delbert L. Thomas, Jr.**, Watervliet, MI (US); **William S. Otte**, Stevensville, MI (US); **Lorraine Joan Westlake**, Eau Claire, MI (US)

(73) Assignee: **Gast Manufacturing Corporation**, Benton Harbor, MI (US)

(**) Term: **14 Years**

(21) Appl. No.: **29/193,219**

(22) Filed: **Nov. 5, 2003**

(51) LOC (7) Cl. **15-02**

(52) U.S. Cl. **D15/9**

(58) Field of Search **D15/7-9; 417/321, 417/410, 413.1, 415, 423.3, 486, 521, 534; 415/148**

(57) **CLAIM**

The ornamental design for a compressor, as shown and described.

DESCRIPTION

FIG. 1 shows a perspective view of a compressor which incorporates the design of the present invention.

FIG. 2 shows a top view of the compressor of FIG. 1.

FIG. 3 shows a bottom view of the compressor of FIG. 1.

FIG. 4 shows a back or rear view of the compressor of FIG. 1.

FIG. 5 shows a front view of the compressor of FIG. 1.

FIG. 6 shows a right side view of the compressor of FIG. 1; and,

FIG. 7 shows a left side view of the compressor of FIG. 1.
